UNITED STATES PATENT OFFICE.

MONTGOMERY WADDELL, OF NEW YORK, N. Y.

LIFTING-BRIDGE.

SPECIFICATION forming part of Letters Patent No. 693,467, dated February 18, 1902.

Application filed October 1, 1901. Serial No. 77,181. (No model.)

To all whom it may concern:

Be it known that I, MONTGOMERY WADDELL, a subject of the King of Great Britain, residing in the city, county, and State of New York, have invented a certain new and useful Improvement in Lifting-Bridges, of which the following is a specification.

An ideal lifting or bascule bridge should present the following conditions: The tilting section of the bridge should be balanced so as to require a minimum of effort to move in all positions of the bridge, when fully raised the whole span width should be clear for passage of vessels without waste of room on the piers, and the entire bridge and its counterweight and operating means should preferably remain always above ground, so as to avoid pits or cuttings in the abutments or piers.

It is the main object of my present invention to provide a lifting or bascule bridge presenting all the above advantages and at the same time to so mount and guide the counterweight that it may be made as light as possible, thus reducing the total weight of the moving structure, and thereby reducing its inertia and its first cost.

My invention is illustrated in the accompanying drawings, wherein—

Figure 1 is a diagram illustrating the mathematical principles involved in my device for mounting and guiding the counterweight. Fig. 2 shows a form of bridge in which the exterior directing or limiting means is rigid. Fig. 3 shows a form of bridge wherein a flexible exterior directing means is employed. Fig. 4 shows a deck-bridge of the same class; and Figs. 5 and 6 are a top view and an end view, partly in section, respectively, of the preferred novel means for applying power to open the bridge.

In Fig. 1 the lower chord of a bridge is indicated at 1 in a half-raised position. The counterweight is shown at 2. A guide 3 is fixed to the bridge, so as to turn with it around the center of motion, which may be a pivot, as shown at 4. This guide carries the counterweight 2, which may be mounted thereon in any desired manner so long as the precise path of the counterweight is determined by said guide.

It is one of the fundamental principles of

my invention that a guide 3 is employed to lead the weight 2 toward the center of movement 4 of the bridge when said bridge tips upward and that this motion toward the center of movement is further determined by an exterior directing means, which may be a rigid arm or, as preferred by me, a flexible cable. Where a cable is used, one end is anchored, as at 5, to a point fixed upon the shore, the other end being fixed to the counterweight. The cable passes over a pulley 6, preferably fixed upon the bridge itself. This is the form intended to be represented in diagram in Fig. 65. 1. In this form of bridge the counterweight acts in a dual capacity. It forms a movable-pulley counterweight, since its supporting-cable passes over a pulley movable with the inshore end of the bridge. At the same time instead of descending freely in a vertical line it is supported upon a guide 3, also on the inshore end of the bridge, and by pressure upon said guide it acts as a direct counterweight. 75

If we assume the center of gravity of the bridge itself independently of the counterweight to be at *a*, the weight of the bridge being represented by the line *W*, and if the vertical line through the center of movement be *bc*, then *ac* is the lever-arm of the downward or positive turning moment exerted by the weight *W* of the bridge. Now this turning moment is opposed by the two efforts into which the gravity of the counterweight 2 may be analyzed. The indirect effort is that which is opposed by a stress in the cable 7. The direct effort is the simple weight *w* of the body 2. Suppose the vertical line *de* to represent in length and direction the quantity and direction of this last or direct effort. Then if the line *df* be a continuation of the direction assumed by the cable 7 near the weight 2 and a perpendicular *ef* is drawn to a line *dg* tangent to the guideway 3 at the point occupied by the weight 2 the line *df* will represent by its length the stress in the cable 7. By drawing a perpendicular to the inshore direction of the cable 7 from the point 4 the lever-arm *4^h* is obtained, which multiplied by the stress *df* (called *s*) gives the turning moment of said stress tending to tilt the bridge. The line *eb* is the lever-arm of the direct effort exerted by the body 2, and the

moment is found by multiplying the weight of the body 2 by the arm eb . Now in order to avoid all resistance to movement of the bridge either way directly due to its weight 5 the following equation should be true:

$$W \times ac = w \times eb + s \times 4^h.$$

Where W is the weight of the bridge, w is the weight of the body 2, and s is the stress in the 10 cable 7. By properly shaping the guide 3 and locating it properly with relation to the pulley 6 and anchorage 5 the above equation can be made true for all positions of the bridge. The proportions and locations in any 15 given case can be found by an engineer by following the principles of turning moments well understood. By the use of this contrivance the counterweight can be made quite small relatively, and even in such a case as 20 that shown in Fig. 4, for example, this weight may be made less than that of the bridge.

Inspection of Fig. 1 will show that as the tangent dg to the guide approaches the vertical (which it does when the bridge closes) 25 the perpendicular eg will cut the line df farther and farther from d , and this increase will take place faster than the decrease in the lever-arm eb of the direct effort. Thus is secured an increased indirect effort, giving 30 an increased total negative turning moment to correspond and counterbalance the increasing positive moment of the bridge as it approaches the horizontal.

In the arrangement indicated in Fig. 3 a 35 counterweight 1.32 times the weight of the bridge will suffice.

It is of course to be understood that while a perfect neutral balance is desirable over a large part of the total opening and closing 40 movements circumstances will usually make it desirable to depart from this condition at certain points in the travel of the bridge. For instance, it may be desired to balance the bridge so that it has a slight closing or down- 45 ward tendency near the entirely open position. This causes a gentle stop, avoiding shock as the opening bridge comes to rest and giving a ready return when the bridge is to be closed again. On the other hand, it will 50 often be well to produce the same effect in or near the closing position, so that there is a certain tendency of the bridge to open when closed. Appropriate locking devices of any well-known type may of course be used. It 55 is therefore to be understood that my invention is not limited to bridges perfectly balanced in all positions, and it is one of the advantages of my device that it lends itself to indefinite modification in this particular at 60 will.

The exterior confining means need not be a cable. As shown in Fig. 2, a rigid arm 8 may be used, which is pivoted to a suitable anchorage 9. On the end of this arm is the counter- 65 weight 2, running upon a guide 3 of suitable form. As will be seen from the dotted lines in Fig. 2, the counterweight is made to run

down along the guide 3 to a position near the center of movement 4 of the bridge. The contrary movement occurs on closing the bridge. 70 In this form of bridge, as in the others, the span is clear from pier to pier and all parts of the bridge and its accessories are above the pier-head, as shown. This form of my invention may be used with advantage in 75 deck-bridges.

Fig. 3 exhibits the very simple form to which a practical bascule-bridge is reducible when made in accordance with my invention. Here a cable 7 is used, running over the pulley 6, while the counterweight attached to the end of said cable runs in a guide 3 of very simple curved form. In the form actually shown this curve is the arc of a circle. As shown in dotted lines, when the bridge is open 85 the counterweight is brought near to the center of movement 4. In this figure I have shown a preferred means for applying power in opening the bridge. This consists in an operating-arm 10, pivoted to a fixed anchorage 11 90 and carrying at its movable extremity gearing 12, adapted to work in a rack 13, conveniently placed upon the bridge. The details of this device are explained hereinafter. Inspection of the parts of Fig. 3 shown in dotted lines will indicate the relative movements 95 of the bridge and its operating-arm.

In Fig. 4 is shown a deck-bridge provided with a preferred form of my invention where-in a counterweight actually lighter than the 100 bridge structure may be used. In this form two movable pulleys 6 and 6^a are used, and the weight 2 runs in a substantially straight guideway. The anchorage of the cable 7 is accomplished through the operating-arm 10, 105 to the extremity of which it is fixed. The location of the pulley 6^a is such that before the gearing 12 comes opposite the pulley the cable 7 acts to aid in tilting up of the bridge, and when said gearing advances materially 110 beyond the pulley 6^a said cable tends to retard movement of the bridge. These effects can be made to correspond, respectively, to a time before and after the center of gravity reaches a vertical through the center of movement 4. The gearing 12 is made to turn in 115 the rack 13 for operating the bridge by means of any appropriate motor either on the bridge or elsewhere; but I prefer to use a motor standing upon or near the pier, as shown at 120 14. The means for transmitting power from such a motor to the gearing 13 are illustrated in detail in Figs. 5 and 6. The arm 10, pivoted at 11, carries a primary gear 15, which drives the shaft 16 by any means—such, for instance, 125 as the bevel-gears 17 and 18. The gear 15 may be driven in any desired way—as, for instance, by the pinion 19 on the shaft of an electric or other motor 14. The shaft 16 turns in suitably-placed bearings 21 and extends 130 to the outer end of the arm 10, where it carries a bevel-gear 22, meshing with a like gear 23 to drive a shaft 24, carrying a pinion 12. This pinion meshes with the rack 13, carried

in any suitable manner on the bridge. I prefer to confine the pinion 12 by some such means as shown in Fig. 6. Here the channel-bar 25 carries the rack 13 on its upper side, while tracks 26 and 27 run along inside the bar 25 on both sides. A frame 28 carries the outer bearing of the pinion 12 and also carries the pulleys 29, adapted to run on one or the other of the tracks 26 27. In Fig. 6 is shown the small clearance maintained between one or the other track and these wheels. This is necessary to allow free turning of the wheels 29 at all times. The pinion 12 should have teeth deep enough to permit of movement of the pulleys 28 from track to track without causing disengagement. It will be understood that the wheels 29 will run upon one or the other of the tracks provided, according to whether a pull or a push is exerted in the arm 10. The frame or carriage 28 is pivoted upon the hub 30, carried by the extremity of the arm 10, to accommodate the varying angle between these two incident to movement of the bridge.

25 A variety of operating means may be employed with my improved bridge and many other modifications may be made in the forms herein specified without departing from the spirit of my invention. I am therefore not 30 to be understood as limiting myself to the precise details herein shown and described.

What I claim is—

35 1. In a bascule-bridge, a counterweight and a guideway for the same fixed on said bridge and extending upward from near the center of movement of said bridge when the same is closed.

40 2. In a bascule-bridge, a counterweight, a guideway for said counterweight on said bridge extending upward from near the center of movement of said bridge when the same is closed and means attached outside of said bridge for directing the movement of said counterweight upon said guide.

45 3. In a bascule-bridge, a counterweight, a guideway therefor on the bridge and a flexible cable anchored outside of the bridge for limiting the movement of said counterweight upon said guide.

50 4. In a bascule-bridge, a counterweight, means fixed to said bridge for guiding said

counterweight, and a flexible cable co-operating to support said counterweight.

5. In a bascule-bridge, a counterweight, a guideway therefor fixed to the bridge, a flexible cable attached to said counterweight and anchored outside of the bridge and a pulley on the bridge over which said cable passes.

6. In a bascule-bridge, a movable-pulley counterweight and a guideway fixed to said bridge for guiding said counterweight.

7. In a bascule-bridge, a counterweight, a flexible cable attached to said counterweight at one end and anchored at the other end and a guiding means for said counterweight fixed to the bridge making a varying angle with said cable during movement of the bridge.

8. In means for raising bascule-bridges, an anchorage, a connecting device rotatably fixed thereto for transmitting the operating strain and power-transmitting means attached to the end of said connecting device directly tending to make said end travel along a predetermined path on said bridge.

9. In a means for raising bascule-bridges, a rack on the bridge, a traveling gear-wheel engaging therewith, a motor for turning said gear and means anchored pivotally outside of said bridge carrying said gear.

10. In a means for raising bascule-bridges, a rack on the bridge, a traveling gear-wheel engaging therewith, a pivoted operating-arm carrying said gear-wheel, a motor outside of said bridge and transmitting means between said motor and gear-wheel carried by said operating-arm.

11. In a bascule-bridge, a counterweight, a guideway therefor, two pulleys on said bridge and a flexible cable passing over said pulleys and attached to said counterweight and to an anchorage outside of said bridge at its two ends respectively.

12. In a bascule-bridge, a counterweight, a guideway therefor, two pulleys on the bridge, a pivoted operating-arm and a flexible cable passing over said pulleys attached at one end to said counterweight and at the other end to said operating-arm.

MONTGOMERY WADDELL.
